REVERSIBLE MOTOR CONTROLLED PORTABLE IRONER WITH SELF-ACTUATING CLUTCH

Archibald H. Davis, Sandusky, Thomas Harris, East Cleveland, and Edward C. Swiluk, Cleveland, Ohio, assignors, by direct and mesne assignments, to The Apex Electrical Mfg. Co., Cleveland, Ohio, a corporation of Ohio

Application August 6, 1946, Serial No. 688,662

13 Claims. (Cl. 38—59)

1

This invention relates to an electric ironer, more particularly to an electric ironer of the type which has a fixed, heated ironing shoe and a rotatable drum member which automatically moves into position to press the fabric against the shoe and rotates to effect the ironing.

It is an object of this invention to provide a compact and simple mechanism for rotating the drum and positioning it with respect to the shoe, all of which mechanism is housed within the drum itself, thereby reducing the number of exterior obstructions and interferences which might trouble the operator.

In portable ironers which must be adapted for use on a standard height table, any increase in base height due to the placement of mechanism therein either results in an increase in height of the ironing drum and shoe or a decrease in clearance between those parts and the base, both conditions being undesirable. By placing all mechanism in the drum and none in the base, base thickness may be kept to a minimum.

One of the critical operations in using ironing machines is that of placing the fabric to be ironed on the drum or shoe in the proper position and insuring that it is properly positioned when the roll forces the fabric against the ironing shoe. This is best done if the operator can use both hands to position and guide the fabric, so it is highly desirable that the ironer be automatic in the sense that the rotation of the drum and positioning of the drum against the shoe can be initiated and controlled without requiring use of the operator's hands and without requiring any complex series of distracting control operations on the part of the operator. Accordingly, it is another object of this invention to provide an automatic ironing mechanism in which the motor is started, the drum is positioned against the shoe and is also started turning by merely pressing a foot, knee or other control switch in one direction.

It is another object of our invention to so design the mechanism that the operator need do nothing more than release pressure on the same switch in order to cause the drum to return to its normal position and stop rotating, ready to receive the next piece of goods. This is accomplished by the novel and simple mechanism described in detail in the description which follows, without requiring any mechanical clutches that must be controlled by the operator.

Still another object of our invention is to

2

provide an effective cooling for the motor to dissipate heat imparted to it by the shoe and drum. Briefly, this is accomplished by extending the motor shaft through the reduction gear housing and attaching a fan blade to the shaft extension, and providing passageways for cooling air in any obstructing parts of the mechanism.

Reference is made to co-pending application No. 688,663, filed by Archibald H. Davis, August 6, 1946, and assigned to The Apex Electrical Mfg. Company, Cleveland, Ohio, which co-pending application claims structure broadly wherein the ironer is completely controlled by operation of a switch controlling a reversible electric motor. The claims in this application are directed specifically to structure wherein a self-actuating clutch is employed in connection with a reversible motor although the motor switch remains the sole control medium for the ironer as in the broader aspects of the invention.

These and other objects will be apparent as the following detailed description of our invention proceeds.

In the drawings:

Figs. 1 and 2 are external views of the novel ironer showing that it is entirely free from external mechanism;

Fig. 3 is a view of part of the drum member with parts broken away to show the driving gear and driving key;

Fig. 4 is a perspective schematic representation of the basic mechanism employed to produce the objects of our invention previously described. In this figure the parts are shown schematically for purposes of illustration and many of the parts are somewhat elongated to avoid visual interference of the parts;

Figs. 5 and 6 illustrate the manual drum position linkage and spring relief mechanism, Fig. 5 showing it in normal position and Fig. 6 in a retracted position;

Figs. 7—9 are end elevations of the portion of the mechanism which causes the novel automatic action and positioning of the drum. Fig. 7 shows the parts in their normal retracted position, the position being that which would occur just before the control switch is pressed to start the ironer. Fig. 8 shows an intermediate position of the drum as it moves toward the shoe. Fig. 9 shows the drum in its forward position ready for ironing; and

Fig. 10 is a schematic diagram to illustrate the principles of how the control switch and

the automatic stop switch may be connected to the motor. This figure is not intended to show actual electric wiring, it merely illustrates the function which is produced, the actual wiring being determined by the type of motor and the available current supply.

In Figs. 1 and 2 can be seen the base structure B, the support arm 1 which carries the heated shoe S, and the metal ironing pressure plate 2. Another fixed arm 3 supports the drum D. The 10 cover plate 4 covers the manual positioning and release mechanism which will be described in detail later. Suffice to say at this time that the control handle 5 enables the operator to retract the drum manually at any time. The end plate 6 is apertured as at 7 to permit air circulation by a fan mounted in the drum.

In Fig. 3 part of the drum D is shown; it carries a fabric cover 8, a fragmentary portion of which is illustrated. There is also an internal ring gear 9 which is driven by a pinion 9a shown in Fig. 4. A part of the drum is also broken away in Fig. 3 to show a key 14 which drives a hub member H in the operating mechanism as will be described presently.

In Fig. 4, the drum support member 3 has rotatably mounted therein a shaft 10 and this shaft, in turn, supports sleeve 11 which is fixed to an arm A, mounted for independent rotation upon the shaft 10. A support arm or bar 12 is keyed to the arm A, this arm forming a support for the motor M and also representing the center of rotation of the drum. The frame or housing of motor M is mounted on bar 12 by any convenient means indicated generally at 13 and the motor is also provided with a gear reduction R so that the pinion 9a may be driven at the required relatively slow speed.

The motor M may be series wound to automatically accommodate the ironing speed to the load at hand, this being a desirable feature. Since, as will appear in the following detailed description, the motor must be reversed to accomplish certain objects of this invention, use of a series motor has another advantage in that such motors are readily reversed without need for split phase field windings, capacitors and the like commonly found in squirrel-cage induction motors. I contemplate that my device could be fitted with shunt or a squirrel cage motor of any type but use of a series motor has the advantages herein mentioned.

The fan F is mounted upon a shaft member which is mechanically an extension of the motor shaft and which may rotate at motor speed. Forward of the motor a driving member or element H is mounted for independent rotation upon the supporting bar 12. Member H is driven by the key 14 on the drum, which key engages a recess or slot 14a in the periphery of the member H. Member H is apertured as at 15 for air circulation and is connected to and drives a partial revolution clutch hub 16 which plays an important part in the operation of the device as will be described. The far end of the drum is provided with a centrally apertured closure flange which is supported for rotation on bearing 9b. This flange will also have cooling apertures to permit circulation of air by the fan.

The helical wire clutch W is wrapped around the hub 16 so that it has a frictional engagement with the hub. The ends of the wire W may be bent outwardly as at 17 and 18 and the wire W is preferably made of spring steel of high tensile strength. The driven member, that is the member which is driven by the clutch wire W, com-

prises a pair of arms 17a and 18a which are rotatably mounted on the shaft 12 that supports the drum. In the preferred construction this mounting in the form of a cam member C which serves not only to couple and mount the arms 17a and 18a so that they may be driven, but has the additional function of acting as an operator or re-acter for moving the bar 12 and, hence, the drum to and from the shoe. The cam member C, rotatably mounted on shaft 12, forms the third part of the clutch arrangement, the general action being that the spring wire W clutches together hub member H and the cam C. Cam C has a pair of arms 17a and 18a attached thereto or integral therewith for co-action with the extension arms 17 and 18 of the clutch spring W.

Cam C is formed with circular portions 20 and 21 the centers of which coincide with the center of the shaft or bar 12. The cam is also formed with lift edges 22 joining the two edges 20 and 21, the edges 22 lying in a circle the center of which lies below that of arm 12. The cam surfaces 22 lie in a circle with a center midway between and in line with rollers 24 and 25 at the two extreme positions of the cam. At intermediate positions of the cam such as that shown in Fig. 8, the center of the circle containing surfaces 22 drops slightly below the line connecting the rollers so that there is a small clearance at the non-reacting roller. A cam follower arm member 23 is mounted to turn with the support shaft 10 and has cam follower rollers 24 and 25. As will be explained presently, it is the action of cam C acting as a first operator and reacting against the other operator in the form of normally fixed cam rollers 24 and 25 which causes the arm A and hence the drum to move to and from the shoe. Likewise, these same members interact to form stop means at each extreme of the drum's motion.

In order that the clutch W may be disengaged at proper times in the cycle, the arm A carries another arm 26 which mounts a clutch release pin 27, the pin being positioned in the path of motion of one or the other of the spring arms 17 or 18, depending upon the direction of rotation of the hub member H. Bracket 28 is also attached to the arm A for mounting a reverse limit switch 29 where it will be engaged by a member carried by the cam C. The majority of the supporting bracket 28 has been broken away so that the parts behind it may be clearly seen. A flange plate 30 or the like may be provided attached to the sleeve 11 in order to mount an end closure plate 6 which plate fits within the drum and is apertured for circulation of air.

At the right of Fig. 4 can be seen a simplified view of the manual positioning means and the spring pressure mechanism. This mechanism serves the dual purpose of providing a resilient pressure between the drum and shoe during ironing or in case large objects pass between those parts, and of providing for manual separation of the drum and shoe at any desired time. The supporting shaft 10 supports the entire drum mechanism upon pedestal 3 and shaft 10 carries the crank arm 31 which arm is pivoted by pin 32 to a link 33. The lower end of the link 33 may be slotted as at 34 and the slot receives the pin 35 mounted on the manually positionable crank 36. The crank 36 is pivoted in the support member 3 as at 37 and is controlled by the hand lever 5. The spring 38 is anchored by pins 32 and 35, the purpose of this spring being to provide a yielding pressure during ironing.

The mechanism just described appears in Figs.

5 and 6 in two positions. For the moment, assume that the position of the shaft 10 determines the position of the drum with respect to the shoe. This is actually the case when the drum is in either of its extreme positions as will be explained presently. In Fig. 5 the hand lever 5 has been pulled back so that its pivot pin 35 is just to the right of a line connecting the pivot pin 32 on the crank 31, and the pivot 37 for the control crank arm 36. Thus, spring tension tends to rotate crank arm 36 counterclockwise but this may be prevented by a stop 41 acting against the crank 36 or by having the lever 5 engage some fixed part of the support mechanism. In addition, tension of the spring 38 tends to bring the crank arm 31 down and move the drum toward the shoe but this is prevented by stop pin 39. The parts are arranged, however, so that as the roll engages the shoe pressure on the drum tends to rotate the shaft 10 clockwise and the spring 38 stretches as the crank 31 is turned.

In Fig. 6 the control lever 5 has been positioned rearwardly and the control crank 36 passes to the other side of the imaginary line referred to between the two pivot pins. Link 33 thereby lifts the crank arm 31 and rotates the shaft 10, which withdraws the drum from the shoe. A positive stop 40 may be provided for the retracted position or an engagement between arm 5 and a fixed part may serve to limit retraction except in this case further retraction of arm 31 is resisted by the force of spring 38.

Figs. 7, 8 and 9 clearly illustrate the action of the clutch mechanism and of the positioning mechanism controlled by shaft 10 previously referred to. If the following description of Figs. 7-9 is read in conjunction with the schematic diagram shown in Fig. 4, a clear understanding of the detailed operation of the clutch mechanism and an overall orientation of how the parts are positioned with respect to one another will be had. Starting with Fig. 7, an elevation view of the member H, the cam, the wire clutch W and the cam follower arm and drum support arm A are shown. The mechanism shown in Fig. 7 is drawn in the position that it would assume if the operator had released the control switch referred to previously, and the drum had automatically withdrawn and had stopped rotating. As indicated by the arrow, the direction in which the drum rotates in order to iron is assumed to be counterclockwise. Now, as the control switch is moved to close the forward circuit, as seen in the wiring diagram in Fig. 10, the motor should start rotating in its forward direction and due to the gearing and drive to the driving hub member 16 shown previously, that member will start to rotate in the direction of the arrow. Since the spring clutch wire W has a frictional engagement with the hub 16, rotation of the member H carries the spring W with it, and the arm 18 on the spring member W tends to be carried away from the arm 18a on the cam C. The arm 17, which had formerly been pressed against the release pin 27 so that the wire was slightly spaced from the hub 16 as at 42, will now be turned away from the release pin. As the hub member 16 carries the wire W and the arm 17 away from the pin 27, the end of the wire adjacent arm 17 is permitted to spring back against the hub and remove the clearance shown at 42. When this occurs the parts are so related that the arm 17 is carried against the cam arm 17a. With the clutch arrangement of the sort shown here, this immediately causes the wire W to be

wrapped around and firmly clamped to the hub 16 and the wire W now tends to move with the hub 16 and hence with the member H. Since the arm 17 of the clutch wire is now locked to the tub member H, it will carry the arm 17a and hence the cam C along with it. The cam C is mounted for independent rotation on the supporting shaft 12 and it will be noted that a lift portion 22 of the cam will be moved under the roller 25 which roller is fixed to the stationary support shaft 10.

Since the shaft 10 is held stationary by the manual positioning and spring release means shown in Figs. 4, 5 and 6, in normal operation 15 the roller support arm 23 does turn. However, it will be noted that arm A is free to turn on shaft 10 as can be seen in Figs. 4 and 7. Therefore, as the cam C is rotated by the clutch, the lift portion 22 reacts against the roller 25 and forces the entire drum supporting mechanism to the left in the figure so that arm A pivots upon shaft 10.

The forward cycle is shown partially completed in Fig. 8. Arm A has been forced towards the shoe, and the lift portion 22 of the cam is continuing to react against the fixed roller 25. The other roller 24 of the cam (broken away for clarity) is engaging a surface approximately concentric with that engaged by the roller 25 so that as the arm A is moved to the left to increase the distance of the roller 25 from the center of the shaft 12, the surface engaged by roller 24 becomes a corresponding distance closer to the center of the shaft 12. It will be noted in Fig. 35 8 that the arm 17 is driving the cam arm 17a and that all clearance is taken up between the clutch wire and the hub and, as can be clearly seen in Fig. 4, this action tends to wrap the wire around the hub and to increase the driving 40 action of the clutch.

In Fig. 9, the forward cycle is completed. The action just shown in Fig. 8 is continued until the arm 18 of the wire W is carried against the release pin 27 which, as can be seen in Fig. 4, is mounted on the arm A. When this happens 45 the adjacent end of the wire W is lifted from the hub 16 and the force of the pin 27 against the spring arm 18 tends to unwrap the wire from the hub 16 providing a clearance as at 43. Thus, the wire W no longer tends to be driven by the hub, and arm 17 of the wire will no longer tend 50 to rotate the cam C by means of cam arm 17a.

Another action occurs at this point in that the roller 24 engages the surface 29 of the cam, which surface is a segment of a circle having its center 55 corresponding to the center of the shaft 12. With this, the center of shaft 12 cannot move any closer to the fixed roller 24 so that the arm A cannot pivot to the left any further, and motion of the drum towards the ironing shoe is 60 stopped. It will be remembered that the rollers 24 and 25 are maintained in a fixed position by the shaft 10 during normal operation of the device. Roller 25 may now ride upon a circular portion 21 of the cam, which surface also has for 65 its center the center of shaft 12. Thus, it would be possible to continue rotation of the cam C without changing the position of the drum relative to the base structure, because both rollers are merely engaging circular cam edges with centers corresponding to that of cam rotation. Furthermore, if the cam C were rotated so that both rollers were on the circular portions 20 and 21 of the cam, any attempt to pivot the arm A in either direction about shaft 10 would be resisted 70 by the rollers 24 and 25.

It will be noted in Fig. 9 that the surface 22 of the cam, which engages roller 25, exerts a powerful wedging action near the end of the cycle tending to urge the arm A towards the left. Since the lift of the cam is relatively small towards the end of the cycle, a given amount of torque tending to rotate the cam results in a high pressure or wedging of the ironing drum against the shoe. Even if the cam is designed so that the roller 25 never quite rides on the circular portion 21, any pressure against the drum and arm A tending to move it back would, due to reaction against the roller, tend to rotate the cam clockwise. However, since the lift of the cam is small near the end of the cycle, it is possible that the friction forces resulting from such pressure would prevent any resultant action tending to rotate the cam and even if such reaction were present, it would be very slight and would merely turn the cam clockwise enough to carry the spring arm 18 away from stop pin 27 causing the spring W to again wrap around the hub, re-engage the clutch, and restore the cam to its previous position. It will also be noted that when the drum assumes the position shown in Fig. 9, since the clutch is released, the drum can continue to rotate without encountering any resistance from the clutch and drum positioning mechanism.

When the operator desires to have the drum withdrawn from the shoe, he merely releases the control switch which, as shown in the diagram of Fig. 10, reverses the motor. When the motor reverses, the arm 18 of the spring W is carried away from the release pin 27 and towards the cam arm 18a, and when the arm 18 engages the cam arm 18a, the spring is again wrapped around the hub 16 and further reverse rotation of the motor, hub and spring drives the cam C in a clockwise direction. Now, the portion of the cam 22 which engages roller 24 acts as a lift portion of the cam and since the roller 24 is stationary, the shaft 12 and the entire assembly is moved back towards its original position. When the initial position is reached, the arm 17 is brought up against pin 27 which releases the clutch and stops further rotation of the cam as seen in Fig. 7. Now shaft 12 and arm A cannot move any closer to roller 25 because circular portion 20 of the cam engages roller 25. Since cam portion 20 is concentric with support 12 the roller remains at a fixed minimum distance from the arm A. Likewise when the shaft 12 and arm A are forward roller 24 engages the other terminal surface of cam 20 with which shaft 12 can get no closer to roller 24. Thus, the portion 20 of the cam acts as a stop for both directions of drum motion.

It will be noted in Fig. 4 that the normally closed limit switch 29 is positioned to be engaged and opened by cam arm 17a when the mechanism assumes the relationship shown in Fig. 7. Limit switch 29 does not appear in Fig. 7 in the interests of clarity, but it is shown in Fig. 4 and it is so arranged that when the arm 17a reaches the position shown in Fig. 7 (and also in Fig. 4) the limit switch is opened. This opens the reverse circuit of the motor and the motor and hence drum rotation thereupon stops. The principle of the circuit is illustrated in Fig. 10 wherein release of the control switch has caused it to close the reverse circuit for the motor and at the end of the cycle the operator arm 17a has engaged the reverse limit switch, to open the reverse circuit and stop the motor. All the operator needs

to do to initiate the ironing cycle is to close the control switch so that the motor will start in the forward direction. Of course, if the switch is spring biased as shown in Fig. 10, the operator must hold the switch closed to continue ironing.

It can be seen that due to the contour of the cam C and the relationship of the arm 23 which carries rollers 24 and 25, that the extreme fore and aft positions of the drum are determined by the position of the arm 23. As has been previously described, arm 23 is mounted on shaft 10 which, in turn, is rotatably mounted in the support structure 3. Also, it has been seen that the control structure and spring release structure determine the position of the shaft 10 and hence determine the two extreme positions of the drum. It will also be noted that in the extreme retracted position, retractions due to manual crank motion and due to the automatic retract motion are additive, providing ample clearance space between drum and shoe for cleaning or steaming the ironing surface.

It has been shown how any backward pressure against the drum, i. e., pressure tending to force it away from the shoe, is transmitted from the cam C to the roller 25 and hence to the shaft 10. If this pressure is great enough the shaft 10 can rotate clockwise against the force of the spring 38. Furthermore, if the cam C is turned until the rollers are on the circular portions 20 and 21 of the cam which have their centers coinciding with that of shaft 12, there will be no reaction from this pressure tending to rotate the cam.

If the operator desires to use the ironer for pressing, he need only place the switch for forward motion until the drum moves against the shoe and then place the switch in its intermediate position which prevents drum rotation.

Having completed the detailed description of the invention, it is contemplated that certain modifications thereof may be made. We have illustrated our invention in a simple form so that the basic principles thereof may be clearly understood and have not attempted to illustrate complicating design details. We have shown the spring wrap-around clutch because it is a very simple, rugged and effective device, but contemplate that the word "clutch", as used in the appended claims, will include any other device which can be utilized to function according to the principles laid down in this specification.

Likewise, we have shown a cam operator mechanism to control the position of the drum against the relatively stationary reaction member, but we contemplate that the same could be accomplished with other designs without departing from the spirit of the invention.

We have illustrated the device on an ironer of the type wherein the shoe is positioned between the operator and the roll, but the mechanism is equally well adapted for use on an ironer wherein the shoe is positioned behind the drum.

It can be seen that we have provided a mechanism which is unusually simple to control in that the operator need only press a switch to start the entire mechanism in operation for ironing and release the same switch to withdraw the drum from the shoe and cause the drum to stop rotating, there being no manual clutches or other controls for normal operation.

Also, since the motor and all mechanisms are in the drum, there need be no gear box in association with the drum support pedestal. This reduces the obstruction at the supported end and

also reduces the overall length of the ironer without sacrificing roll length. A reduction in overall ironer length is particularly helpful with a portable ironer in that it facilitates stowage in the standard width of kitchen cabinet.

We believe ourselves to be the first to devise such an ironer as claimed and contemplate that the modifications referred to above as well as modifications in design details which are common knowledge to all machine designers and others may be made without departing from the spirit of the invention as defined in the appended claims.

Having thus described the present invention so that others skilled in the art may be able to understand and practice the same, we state that what we desire to secure by Letters Patent is defined in what is claimed.

We claim:

1. In an ironer, a base structure, a shoe mounted thereon, a drum support member, means mounting said drum support member on said base structure for motion toward and away from said shoe, a drum rotatably mounted on said drum support member, a member having a hub rotatably mounted on said drum support member, an electric motor having rotor and stator elements one of which is mounted on said drum support member, drive means connecting said drum and said hub for rotation by said other motor element, a spring wire clutch member wrapped around and in frictional engagement with said hub and having an arm portion, a cam member rotatably mounted on said drum support member having abutment means disposed in the path of said clutch arm portions, normally stationary cam follower means mounted on said base structure, said drive means being arranged so that as soon as the motor is started the drum, hub member and clutch spring turn in one direction whereupon the clutch arm portion is carried against and engages the cam abutment means, said clutch member being wrapped around the hub in such a direction that the aforesaid engagement of the clutch arm and cam abutment means tends to further wrap the clutch member against and increase its grip on the hub, said clutch arm portion thereafter turning the cam, said cam acting against said cam follower member to move said drum support member and associated structure toward said shoe.

2. In an ironer, a base structure, a shoe mounted thereon, a drum support member, means mounting said drum support member on said base structure for motion toward and away from said shoe, a drum rotatably mounted on said drum support member, a member having a hub rotatably mounted on said drum support member, an electric motor having rotor and stator elements one of which is mounted on said drum support member, drive means connecting said drum and said hub for rotation by said other motor element, a spring wire clutch member wrapped around and in frictional engagement with said hub and having an arm portion at each end, a cam member rotatably mounted on said drum support member having abutment means disposed in the path of said clutch arm portions, normally stationary cam follower means mounted on said base structure, said drive means being arranged so that as soon as the motor is started the drum, hub member and clutch spring turn in one direction, whereupon one of said clutch arm portions is carried against and engages the cam abutment means, said clutch member being wrapped around

the hub in such a direction that the aforesaid engagement of said one clutch arm portion and cam abutment means tends to further wrap the clutch member against and increase its grip on the hub, said clutch arm portion thereafter turning the cam, said cam acting against said cam follower member to move said drum support member and associated structure toward said shoe, and clutch release means mounted on said drum support mounting means and disposed between said clutch arm portions rotation of said hub past a certain point carrying said other clutch arm portion against said release means thereby tending to unwrap said clutch member against said hub, reversal of said motor carrying said other clutch arm portion away from said release means and against said abutment means to wrap said clutch member against said hub and retract said drum support member.

3. In an ironer, a base structure, a shoe mounted thereon, a drum support member, means mounting said drum support member on said base structure for motion toward and away from said shoe, a drum rotatably mounted on said drum support member, a member having a hub rotatably mounted on said drum support member, a reversible electric motor having rotor and stator elements one of which is mounted on said drum support member, drive means connecting said drum and said hub for rotation by said other motor element, a spring wire clutch member wrapped around and in frictional engagement with said hub and having an arm portion at each end, a cam member rotatably mounted on said drum support member having abutment means disposed in the path of said clutch arm portions, normally stationary cam follower means mounted on said base structure, said drive means being arranged so that as soon as the motor is started the drum, hub member and clutch spring turn in one direction, whereupon one of said clutch arm portions is carried against and engages the cam abutment means, said clutch member being wrapped around the hub in such a direction that the aforesaid engagement of said one clutch arm portion and cam abutment means tends to further wrap the clutch member against and increase its grip on the hub, said clutch arm portion thereafter turning the cam, said cam acting against said cam follower member to move said drum support member and associated structure toward said shoe, and clutch release means mounted on said drum support mounting means and disposed between said clutch arm portions rotation of said hub past a certain point carrying said other clutch arm portion against said release means thereby tending to unwrap said clutch member against said hub, reversal of said motor carrying said other clutch arm portion away from said release means and against said abutment means to wrap said clutch member against said hub and retract said drum support member.

4. In an ironer, a base structure, an ironing shoe element and an ironing drum element, means mounting one of said elements on said base structure, means mounting the other of said elements on said base structure for motion toward and away from said one element, a member having a hub rotatably supported by said base structure, an electric motor having rotor and stator elements one of which is supported by said base structure, constantly engaged drive means connecting said drum element and said hub for rotation by said other motor element, a spring wire clutch member wrapped around and in frictional engagement with said hub and having an arm portion at each end, rotatable abutment means concentric with said hub member and disposed in the path of said clutch arm por-

11

tion, means connecting said abutment means and the mounting means for said other elements for moving said latter element relative to said base structure, said drive means being arranged so that as soon as the motor is started the drum, hub member and wire clutch turn in one direction, whereupon one of said clutch arm portions is carried against and engages said abutment means, said clutch member being wrapped about the hub in such a direction that the aforesaid engagement of said one clutch arm portion and abutment means tends to further wrap the clutch member about and increase its grip on the hub, said clutch arm portion thereafter turning to move said other element toward said one element, and clutch release means supported on the mounting means for said other element and disposed between said clutch arm portions, rotation of said hub past a predetermined point carrying said other clutch arm portion against said release means thereby tending to unwrap said clutch member about said hub.

5. In an ironer, an ironing shoe element, a rotatable ironing drum element, one of said ironing elements being fixed and the other being mounted for relative movement toward and away from the fixed ironing element, a reversible electric motor, a rotatable driving element, means rotatably driving said ironing drum element and said driving element from said motor, mechanism for moving said movable ironing element toward and away from said fixed ironing element, said mechanism comprising a plurality of relatively movable interconnected members, one of said members being fixed and constituting a reaction member, another of said members being movable and connected to said movable ironing element, a clutch resiliently pressed into engagement with said rotatable driving element and frictionally coupling the same to said movable one of said interconnected members of said mechanism so that rotation of said motor in one direction tends to move said movable member relative to said fixed member and thereby move said shoe and drum toward each other, and rotation of said motor in the opposite direction tends to move said movable member in the opposite direction relative to said fixed member and thereby said shoe and drum away from each other, and release means arranged to release said clutch after a predetermined movement of said driving element in either direction.

6. In an ironer, an ironing shoe element and ironing drum element, means mounting one of said ironing elements for motion toward and away from the other ironing element, a reversible electric motor, a rotatable driving element, normally constantly engaged drive means connecting said motor to said drum and said driving element for rotation, mechanism to cause motion of said movable ironing element relative to the other ironing element, said mechanism comprising a plurality of relatively movable interconnected members, one of said members being fixed and constituting a reaction member, another of said members being movable and connected to said movable ironing element, clutch means for coupling said driving element to said movable one of said interconnected members, means causing said clutch means to couple said driving element to said movable one of said interconnected members whenever the motor is started in one direction with the movable ironing element at its retracted position, whereupon said mechanism moves said movable ironing ele-

12

ment toward the other ironing element for ironing, and clutch release means disposed for engagement with said clutch means to uncouple said driving element and said one interconnected member when said movable ironing element reaches its ironing position and means causing said clutch means to recouple said driving element and member whenever the motor is started in the other direction with the movable ironing element at its ironing position, whereupon said mechanism moves said movable ironing element away from the other ironing element, said clutch means engaging said release means when said movable ironing element returns to its retracted position.

7. In an ironer, an ironing shoe element and an ironing drum element, means mounting one of said ironing elements for motion toward and away from the other ironing element, a reversible electric motor, a rotatable driving element, normally constantly engaged drive means connecting said motor to said drum and said driving element for rotation, mechanism to cause motion of said movable ironing element relative to the other ironing element, said mechanism comprising a plurality of relatively movable interconnected members, one of said members being fixed and constituting a reaction member, another of said members being movable and connected to said movable ironing element, clutch means for coupling said driving element to said movable one of said interconnected members, means causing said clutch means to couple said driving element to said movable one of said interconnected members whenever the motor is started in one direction with the movable ironing element at its retracted position, whereupon said mechanism moves said movable ironing element toward the other ironing element for ironing, release means disposed for engagement by said clutch means, engagement of said clutch and release means causing said clutch means to uncouple said driving element and said member, said clutch means engaging said release means when said movable ironing element reaches its ironing position, and means causing said clutch means to recouple said driving element and member whenever the motor is started in the other direction with the movable ironing element at its ironing position, whereupon said mechanism moves said movable ironing element away from the other ironing element, said clutch means engaging said release means when said movable ironing element returns to its retracted position.

8. In an ironer, an ironing shoe element and an ironing drum element, means mounting said drum element for motion toward and away from the shoe element, a reversible electric motor, a rotatable driving element, normally constantly engaged drive means connecting said motor to said drum and said driving element for rotation, mechanism to cause motion of said drum element relative to the shoe element, said mechanism comprising a plurality of relatively movable interconnected members, one of said members being fixed and constituting a reaction member, another of said members being movable and connected to said drum element, clutch means for coupling said driving element to said movable one of said interconnected members, means causing said clutch means to couple said driving element to said movable one of said interconnected members whenever the motor is started in one direction with the drum element at its retracted position, whereupon said mechanism moves said drum

element toward the shoe element for ironing, and clutch release means disposed for engagement by said clutch means, engagement of said clutch and release means causing said clutch means to uncouple said driving element and said member, said clutch means engaging said release means when said movable ironing element reaches its ironing position, and means causing said clutch means to recouple said driving element and member whenever the motor is started in the other direction with the movable ironing element at its ironing position, whereupon said mechanism moves said movable ironing element away from the other ironing element, said clutch means engaging said release means when said movable ironing element returns to its retracted position. 15

9. In an ironer, an ironing shoe element and an ironing drum element, means mounting one of said ironing elements for motion toward and away from the other ironing element, a reversible electric motor and a control circuit for said motor, a rotatable driving element, normally constantly engaged drive means connecting said motor to said drum and said driving element for rotation, mechanism to cause motion of said movable ironing element relative to the other ironing element, said mechanism comprising a plurality of relatively movable interconnected members, one of said members being fixed and constituting a reaction member, another of said members being movable and connected to said movable ironing element, clutch means for coupling said driving element to said movable one of said interconnected members, means causing said clutch means to couple said driving element to said movable one of said interconnected members whenever the motor is started in one direction with the movable ironing element at its retracted position, whereupon said mechanism moves said movable ironing element toward the other ironing element for ironing, and clutch release means disposed for engagement with said clutch means to uncouple said driving element and said one interconnected member when said movable ironing member reaches its ironing position, release means disposed for engagement by said clutch means, engagement of said clutch and release means causing said clutch means to uncouple said driving element and said member, said clutch means engaging said release means when said movable ironing element reaches its ironing position, and means causing said clutch means to recouple said driving element and member whenever the motor is started in the other direction with the movable ironing element at its ironing position, whereupon said mechanism moves said movable ironing element away from the other ironing element, said clutch means engaging said release means when said movable ironing element returns to its retracted position, and electric limit switch means operated by retraction of said movable ironing element to open said motor control circuit as said movable ironing element reaches its retracted position.

10. In an ironer, an ironing shoe element and an ironing drum element, means mounting said drum element for motion toward and away from the shoe element, a reversible electric motor having its stator mounted on the drum element, a rotatable driving element, normally engaged drive means including reduction gearing connecting said motor to said drum and said driving element for rotation, mechanism to cause motion of said drum element relative to the shoe element, said mechanism comprising a plurality of relatively

movable interconnected members, one of said members being fixed and constituting a reaction member, another of said members being movable and connected to said drum element, said drum element being free to turn whenever said motor is energized, clutch means for coupling said driving element to said movable one of said interconnected members, means causing said clutch means to couple said driving element to said movable one of said interconnected members whenever the motor is started in one direction with the drum element at its retracted position, whereupon said mechanism moves said drum element toward the shoe element for ironing, and clutch release means disposed for engagement by said clutch means, engagement of said clutch and release means causing said clutch means to uncouple said driving element and said member, said clutch means engaging said release means when said movable ironing element reaches its ironing position.

11. In an ironer, an ironing shoe element and an ironing drum element, means mounting said drum element for motion toward and away from the shoe element, a reversible electric motor having its stator mounted on the drum element, a rotatable driving element, normally engaged drive means including a reduction gearing connecting said motor to said drum and said driving element for rotation, mechanism to cause motion of said drum element relative to the shoe element, said mechanism comprising a plurality of relatively movable interconnected members, one of said members being fixed and constituting a reaction member, another of said members being movable and connected to said drum element, said drum element being free to turn whenever said motor is energized, clutch means for coupling said driving element to said movable one of said interconnected members, means causing said clutch means to couple said driving element to said movable one of said interconnected members whenever the motor is started in one direction with the drum element at its retracted position, whereupon said mechanism moves said drum element toward the shoe element for ironing, and clutch release means disposed for engagement by said clutch means, engagement of said clutch and release means causing said clutch means to uncouple said driving element and said member, said clutch means engaging said release means when said movable ironing element reaches its ironing position, and means causing said clutch means to recouple said driving element and member whenever the motor is started in the other direction with the movable ironing element at its ironing position, whereupon said mechanism moves said movable ironing element away from the other ironing element, said clutch means engaging said release means when said movable ironing element returns to its retracted position.

12. In an ironer, a base structure, a fixed shoe mounted thereon, drum support means including a support member normally stationary relative to said base structure and an axle member eccentrically mounted on said first member for motion toward and away from said shoe, a drum mounted for rotation about said axle member, a reversible electric motor having its stator mounted on said axle member, driving and driven elements rotatably mounted on said axle member, clutch means for coupling said elements, drive means including reduction gearing connecting said drum and said driving element for rotation by the rotor of said motor, cam means rotatably

mounted on said axle member and connected to said driven element to be turned when the driving and driven elements are coupled, normally stationary cam follower means mounted on said normally stationary drum support member and engaging said cam means to cause motion of said axle member relative to said drum support member in opposite directions when the clutch is coupled and the cam is turned in opposite directions by the reversible motor, means causing coupling of said clutch elements whenever the motor is started in one direction with the drum at its retracted position whereby said drum moves toward the shoe, said last-named means comprising arm means on said clutch means and abutment means on said driven element disposed in the path of said arm means, and means causing coupling of said clutch element whenever the motor is started in the reverse direction with the drum in its ironing position whereby said drum retracts from the shoe, said last-named means comprising arm means on said clutch means and abutment means on said driven element disposed in the path of said arm means, and clutch release means releasing said clutch after the drum has moved from one of said positions to the other, said last-named means comprising abutment means supported on said axle member and disposed in the path of said arm means.

13. In an ironer, an ironing shoe member and an ironing drum member, means mounting one of said ironing members for motion between a retracted position and an ironing position, a reversible electric motor, a rotatable driving element, a rotatable driven element, and clutch means for coupling said elements, normally constantly engaged drive means connecting said drum and said driving element for rotation by said reversible electric motor, mechanism connected to said driven element to cause motion of said movable ironing member relative to the

other member, clutch engaging means for causing said clutch means to couple said elements whenever the motor is started in either direction, means for releasing said clutch means after said motor has driven said driven element a predetermined amount in either direction, said drum remaining in driving connection with said motor after release of said clutch means, said clutch engaging means being arranged to couple said elements when the motor is started in one direction with the movable ironing member at its retracted position, whereupon said mechanism moves said movable ironing member toward the other ironing member for ironing, said release means being arranged to release said clutch means when said movable ironing member reaches its ironing position, said clutch engaging means causing said clutch means to recouple said driving and driven elements whenever the motor is started in the other direction with the movable ironing member at its ironing position, whereupon said mechanism moves said movable ironing member away from the other ironing member, said clutch release means when releasing said clutch means when said movable ironing member returns to its retracted position.
